LOOSE LEAF CLASP BINDER

Herbert S. Chase, Woodmere, N. Y., assignor to Bernard Cahn Co., Inc., New York, N. Y.

Application May 26, 1958, Serial No. 51,079

Term of patent 7 years

(Cl. D6—2)

The essential features of my design reside in the portions shown in solid lines on the drawing.

I claim:

The ornamental design for a loose leaf clasp binder, substantially as shown and described.
